DUMPING CAR.

(Application filed May 18, 1901.)

(No Model.)

2 Sheets—Sheet 2.

UNITED STATES PATENT OFFICE.

GEORGE I. KING, OF DETROIT, MICHIGAN, ASSIGNOR TO AMERICAN CAR & FOUNDRY COMPANY, OF ST. LOUIS, MISSOURI, A CORPORATION OF NEW JERSEY.

DUMPING-CAR.

SPECIFICATION forming part of Letters Patent No. 692,457, dated February 4, 1902.

Application filed May 18, 1901. Serial No. 60,859. (No model.)

To all whom it may concern:

Be it known that I, GEORGE I. KING, a citizen of the United States, residing at the city of Detroit, county of Wayne, State of Michigan, have invented a certain new and useful improvement in Dumping-Cars, of which the following is a full, clear, and exact description, such as will enable others skilled in the art to which it appertains to make and use the same, reference being had to the accompanying drawings, forming part of this specification, in which—

Figure 1 is a top plan view of my improved dumping-car, part of the body portion being removed to show the underframing. Fig. 2 is a side elevational view, one end of said car being shown in vertical section. Fig. 3 is a detail top plan view showing the door-operating mechanism. Fig. 4 is a sectional view on line 4 4, Fig. 3. Fig. 5 is a sectional view on line 5 5, Fig. 3; and Fig. 6 is a detail view showing the pawl-and-ratchet mechanism for the door-operating shaft.

This invention relates to a new and useful improvement in dumping-cars designed especially for use in hauling coke and other light loose loads, the object being to provide a car with a bottom composed of a plurality of hoppers, each of which is provided with an exit for the load, said exits being controlled by suitable doors.

Another object is to construct a car of the character described of structural steel, and in order to obtain maximum cubic capacity, strength, and rigidity with the least amount of dead-weight with respect to the carrying capacity of the car I utilize the side walls as plate-girders, which plate-girders also partially form what might be termed the "top chords" of side trusses, the bottom chords of said trusses being preferably in the form of horizontally-arranged latticed girders supported at their ends by the body-bolsters of the car.

Another object is to take advantage of the arrangement and disposition of the hopper-floor sheets by utilizing said sheets to add strength and rigidity to the structure.

With these objects in view the invention consists in the construction, arrangement, and combination of the several parts, all as will hereinafter be described and afterward pointed out in the claims.

In the drawings, 1 indicates the end sills of the car, and 2 the draft-sills, which draft-sills preferably extend only to the body-bolsters.

3 indicates the body-bolsters, which are preferably continuous from side sill to side sill and I-shaped in section.

4 indicates the side sills, which are preferably in the form of channels with their flanges presented inwardly, said channels being riveted to the ends of the body-bolsters.

5 and 6 are top and bottom cover-plates for the body-bolsters.

7 indicates angles, preferably parallel to each other and extending from bolster to bolster, said angles being preferably on a lower plane than the bottom flanges of the side sill, to which they are connected by lattice-bars 8. The side sills, angles, and lattice-bars form horizontally-arranged latticed girders, which in addition to resisting buffing blows and lateral forces are also placed in tension by forming the bottom chords of the side-truss frames.

9 indicates the side walls of the car in the form of plate-girders, which are supported over the body-bolsters by inclined stiffening-braces 10.

By referring to Figs. 2 and 5 it will be observed that the lower edge of the side sheet is above the side sill and that said side sheet has angles 11 riveted to it, which angles are oppositely inclined or arranged zigzag between the inclined stiffening-braces 10. These angles and inclined stiffening-braces form a series of triangles or A-frames connected together at their upper ends by the side sheet and at their lower ends by the side sill member of the horizontal girder. This structure forms in itself a side truss of great strength, in that part of the top chord or compression member is a deep web in the form of the side sheet or side wall of the car. The side sill member of the horizontal truss par-

tially forms the bottom chord and under load is placed in tension, while the inclined braces 10 and 11 take the place of the usual vertical posts and diagonals commonly found in 5 trussed structures.

So far as the above construction is concerned it is substantially the same in all respects as that shown and described in the United States patent granted to King and Jessen, No. 670,614, dated March 26, 1901, with the exception that the body-bolsters in the present case are continuous from side sill to side sill and there are six instead of two inclined angles between the end stiffening-braces.

12 indicates the sloping end floor-sheets, which at their upper portions are inclined at angles of about thirty degrees, while their lower portions are inclined at angles of about 20 forty-five degrees. The purpose of this difference in inclination is to utilize to the full the available space for the load and at the same time enable the contents of the car in 25 the bottoms of the hoppers to readily and quickly be discharged, the great inclination of the sloping sheets forming the hopper preventing any choking in the exit for the load.

13 indicates the side hopper-sheets, which are riveted at their upper edges to the bottom 30 edges of the side sheets. These inclined hopper-sheets 13 pass inwardly over the angles 7 and thence downwardly to form the vertical side walls of the exit for the load.

14 indicates the side hopper-sheets arranged 35 centrally the car, the upper outer edges of said sheets being riveted to the lower edges of the side sheets 9, while the inner portions of the sheet are bent downwardly over the angles 7 to form vertical walls for the two centrally-located openings for the load.

15 indicates a short cross-ridge riveted to the lower edges of the hopper-plates 14. This cross-ridge is located between and below the plane of the parallel angles 7 and by 45 its angular formation strengthens the inner edges of the hopper-sheets 14, in addition to which it forms a shed for directing the contents of the car through the two centrally-located exits for the load.

50 16 indicates cross-ridges, whose apices practically extend across the entire width of the car. The inclined lower edges are riveted to the edges of the side hopper-sheets 13 and 14. The deepest portion of these cross-ridges 16 terminate approximately on the plane of the angles 7, to which they are secured by appropriate fastening devices. These cross-ridges 55 16 not only serve to support and strengthen the side hopper-sheets 13 and 14, but they 60 also serve to tie the side walls together at points intermediate the body-bolsters, and they likewise tie angles 7 together. In this manner separate and distinct tie-braces may be dispensed with.

65 The sheets forming the side, end, and hopper walls, as well as the cross-ridges, are cut

to the proper shape, suitable marginal flanges being left for the reception of the proper number of securing-rivets. I have not deemed it necessary to illustrate the manner of fastening these sheets together and to their associate parts, as the same is well known and understood to those skilled in the art.

Referring now to Figs. 3, 4, and 5, 17 indicates parallel bars, preferably channels, whose ends are beveled to abut against and be secured to the legs of the cross-ridge 16 by means of rivets and suitable corner connection plates or angles. In addition to strengthening the deepest portion of the cross-ridges 80 these bars 17 provide a support for the door-operating mechanism. The doors 18 for closing the exits for the load are hinged by suitable devices to the legs of the cross-ridges 16, the two doors secured to each cross-ridge being 85 companions and forming a pair. These doors are connected together by yokes 19, whose inner extremities are arranged upon a common pintle 20. The ends of this pintle are received in slots in plates 21, which plates 90 are riveted or otherwise secured to backing-plates 22, these two plates 21 and 22 being of substantially the same shape and secured to the bars 17 by suitable rivets. The plate 21 is reinforced by a rib 22 on its outer face, 95 (see Fig. 5,) while the lower ends of the pairs of plates 21 are connected by a tie-plate 23. The advantage of this construction resides in its simplicity and the ease with which it may be assembled and placed in position. The 100 ends of the pintle 20 are received in the slots in the plates 21, and by providing suitable washers 24 on each side of the yokes 19 where they are strung on the pintle no fastening devices are necessary, as the back 105 plates 22 prevent lateral and longitudinal displacement of the pintle. The lower ends of the slots in the plates 21 are preferably left open, so that by disconnecting the link from the pintle and removing the tie-plate 23 110 the pintle may be dropped through the bottom of the slot for purposes of repairs, &c.

25 indicates a link mounted on the pintle between the washers 24 and pivotally connected at its other end to a rock-arm 26. This 115 rock-arm is formed on the inner end of an operating-shaft 27, mounted in suitable bearings provided on one of the channels 17 and the side sill 4, the outer end of said shaft being formed non-circular for the reception of 120 a suitable wrench, whereby said shaft may be rotated, said outer end also carrying a disk 28, having radial projections for coöperating with pawls 29, whereby the doors 18 125 may be locked in their open or closed positions.

The principle of operation of the type of door shown is old and well known, and I do not claim the same here. However, so far as I am aware the construction and arrangement 130 of the pintle-guides are new.

I will state that the edges of the sheets im-

mediately adjacent the door-opening are preferably reinforced by suitable angles for well-understood purposes.

I am aware that minor changes in the arrangement, construction, and combination of the several parts of my device can be made and substituted for those herein shown and described without in the least departing from the nature and principle of my invention.

10 Having thus described my invention, what I claim, and desire to secure by Letters Patent, is—

1. In a car of the character described, the combination with the side walls, of inclined 15 stiffening bars or braces, side sills located some distance below the side walls, oppositely-inclined members attached to the side walls and to the side sills intermediate said inclined stiffening-braces, and cross-ridges; substantially as described.

2. In a car of the character described, the combination with supporting-bolsters, of side sill members attached thereto, vertically-disposed side walls above the side sills, triangularly-arranged stiffeners for said side walls, sloping floor-sheets attached to the lower edges of said side wall, and cross-ridges attached to the lower edges of said sloping floor-sheets; substantially as described.

3. In a car of the character described, the combination with supporting-bolsters, of horizontally-disposed girders carried thereby, the outer members of said girders serving as side sills, vertically-disposed side walls arranged 35 above the side sills, triangularly-arranged stiffeners for said side walls, sloping floor-sheets attached to the lower edges of the side walls and to the inner edges of the horizontally-disposed girders, and cross-ridges; substantially 40 as described.

4. In a car of the character described, the combination with the side walls, of sloping end sheets having different degrees of inclination; substantially as described.

45 5. In a car of the character described, the combination with side walls, of end sheets whose upper portions are inclined and whose lower portions are also inclined but at a different angle; substantially as described.

50 6. The combination with side walls of sloping end sheets having different degrees of inclination, and inclined side hopper-sheets; substantially as described.

7. In a car of the character described, the 55 combination with side walls, of end sheets having different degrees of inclination throughout different portions thereof, inclined side hopper-sheets, and a cross-ridge; substantially as described.

60 8. In a car of the character described, the combination with side walls, of sloping end

sheets, inclined side hopper-sheets, and cross-ridges of unequal lengths; substantially as described.

9. In a car of the character described, the 65 combination with the side hopper-sheets, of cross-ridges arranged at the upper and lower edges of said hopper-sheets; substantially as described.

10. In a car of the character described, the 70 combination with the hopper-sheets, of a cross-ridge arranged at the upper edge thereof, doors hinged to the legs of said cross-ridge, and a cross-ridge arranged at the lower edge of said hopper-sheets, and against which the 75 free ends of said doors swing; substantially as described.

11. In a car of the character described, the combination with hopper-sheets and sloping end sheets, of cross-ridges 16, doors hinged to 80 the legs of said cross-ridges, and a cross-ridge 15; substantially as described.

12. In a car of the character described, the combination with the sloping end sheet and the end hopper-sheets 13, of the middle hopper-sheets 14, a short cross-ridge arranged between the lower inner edges of the middle hopper-sheets 14, cross-ridges 16 arranged between the upper portions of the hopper-sheets 13 and 14, and doors hinged to the cross-ridges 90 16; substantially as described.

13. In a car of the character described, the combination with girders lying in a horizontal plane, of hopper-sheets whose inner edges overhang and depend from said girders to 95 form vertical walls for the exit-openings for the load, and means for tying said depending vertical walls against lateral displacement; substantially as described.

14. In a car of the character described, the 100 combination with a cross-ridge, of doors hinged to the legs thereof, and bars secured wholly within the cross-ridge for strengthening the same in the absence of center sills and for supporting the door-operating mechanism, 105 substantially as described.

15. In a car of the character described, the combination with the cross-ridge, doors hinged to the legs thereof, bars arranged wholly within the cross-ridge for strengthening the 110 same, guide-plates secured to said bars, and mechanism for operating the doors, part of said mechanism being guided in its movement by said guide-plates; substantially as described.

In testimony whereof I hereunto affix my signature, in the presence of two witnesses, this 14th day of May, 1901.

GEORGE I. KING.
